UNITED STATES PATENT OFFICE.

LAWRENCE DULLIGAN, OF ROCHESTER, NEW YORK.

INSTEP-SUPPORTER.

SPECIFICATION forming part of Letters Patent No. 745,166, dated November 24, 1903.

Application filed July 22, 1903. Serial No. 166,527. (No model.)

To all whom it may concern:

Be it known that I, LAWRENCE DULLIGAN, of Rochester, in the county of Monroe and State of New York, have invented certain new and useful Improvements in Instep-Supporters; and I do hereby declare the following to be a full, clear, and exact description of the same, reference being had to the accompanying drawings, forming a part of this specification, and to the reference-numerals marked thereon.

My present invention relates to improvements in instep-supporters; and it has for its object to produce a device of this character adapted to be worn in the wearer's shoe to reinforce or support that portion of the wearer's foot between the heel and ball, and has for its object to produce a device which can be manufactured cheaply and will retain its shape and not be broken down in use, all as will be hereinafter more fully explained, and pointed out in the claims hereunto annexed.

In the drawings, Figure 1 is a perspective view of an instep-supporter embodying my invention. Fig. 2 is a perspective view of the supporter from underneath, and Fig. 3 is a transverse sectional view on the line 3 3, Fig. 2.

Similar reference-numerals in the several figures indicate similar parts.

To facilitate an understanding of my invention, reference will be had to the herein-shown embodiment thereof, wherein 1 designates an instep-supporter, preferably made of sole-leather and which may be of any desired size and molded or treated in the usual or any preferred manner to properly fit within the shoe and having the upturned edges 2 and 3 to conform to the inner and outer portion, respectively, of the under side of the wearer's foot. In the lower or under side of a support formed in the above manner are made a plurality of longitudinally-disposed slits 4, arranged in pairs and extending to a predetermined depth beyond the surface, said slits being cut at such angles to the surface that they approach as they recede from the surface. These slits are preferably arranged in substantially parallel pairs, and extending from one slit to the opposite slit of the same pair are provided a plurality of thread channels or passages 5, disposed at suitable intervals and extending

inwardly preferably to the greatest depth possible without perforating the opposite or upper surface of the material composing the supporter, and through these channels are interlaced one or more binding threads 6, the intervening portions 7 thereof extending between the passages and lying at the bottom of each slit beneath or beyond the surface of the supporter. An inelastic waxed thread is advantageously employed for this purpose, the relative sizes of the thread and channels being preferably such that when the thread is tightly drawn it will be securely gripped to prevent subsequent loosening, or, if preferred, wax or cement may be employed for this purpose and for sealing the slits to completely conceal the threads. A reinforcement of this character may be readily applied to ordinary shoes at an insignificant cost, the slits being conveniently formed by a knife and the thread passages or channels by a curved awl, the threads being securely protected and concealed below the surface to prevent their destruction from wear and to present a neat appearance. If desired, this stitching can be accomplished by the use of the well-known McKay shoe-sewing machine.

Any desired number of reinforcements may be provided; but for all ordinary purposes only two are deemed necessary, each of which should preferably be located in the curved portions of the upturned edges 2 3, and as the threads are drawn tight and are substantially inelastic that portion of the supporter in proximity to the threads will be rendered rigid or stiffened in a direction both longitudinally and transversely of the support, thereby retaining the upturned edges in their proper shape and position and effectually resisting any forces acting intermediate its ends to bend or disturb the shape of the supporter longitudinally. As the reinforced portion of the supporter will span or bridge the space between the heel and sole of the shoe, the weight imposed upon it when in use will be sustained by the supporter without distortion.

I claim as my invention—

1. An instep-support having its longitudinal edges curved upwardly, a plurality of thread-passages extending transversely of said curved portions and arranged at intervals and threads stitched and interlaced

through said passages and drawn tightly to reinforce said portions in their curved position.

2. An instep - support having upwardly-
5 curved edges and a plurality of passages ar-
ranged transversely thereof, slits connecting
the ends of said passages and threads tightly
stitched or interlaced through said passages,
the intervening portions thereof between said
10 passages lying in said slits.

3. An instep-support having a plurality of
transversely-disposed passages arranged at
intervals and extending to a predetermined
depth from the surface of the support, slits
15 extending longitudinally of said support and
connecting the ends of said passages and sub-
stantially inelastic threads interlaced through
said passages, the intervening portions there-
of between said passages lying in said slits
20 beneath the surface of the support.

4. An instep-support having a plurality of
longitudinally-disposed slits formed in the
lower surface thereof, passages extending to
a predetermined depth beyond the under side
of the support and connecting said slits at 25
intervals, and a substantially inextensible
thread stitched or interlaced through said
passages and drawn tightly to reinforce said
support both longitudinally and transversely.

5. An instep or bridge support adapted for 30
use in shoes consisting of a body portion of
leather or similar material, curved upwardly
at the sides, which latter are reinforced by
threads or cords stitched through the sub-
stance of the upturned sides and extending 35
substantially in the direction of said sides.

LAWRENCE DULLIGAN.
